WATER COOLER

Filed Aug. 13, 1928

FIG. 1.

FIG. 2.

FIG. 3.

FIG. 4.

FIG. 5.

MORRIS RAYMOND,
INVENTOR:

BY Victor J. Evans,
ATTORNEY.

WITNESS:

M. Raymond

UNITED STATES PATENT OFFICE.

MORRIS RAYMOND, OF BROOKLYN, NEW YORK.

WATER COOLER.

Application filed August 13, 1928. Serial No. 299,261.

This invention relates to water coolers for ice-boxes and refrigerators and is an improvement over the cooler shown and described in my co-pending application Serial No. 245,482, filed January 9th, 1928.

The primary object of this invention, like that set forth in the above mentioned pending application resides in a water cooler for use in the ice compartment of a refrigerator 10 in lieu of the usual ice tray for supporting the ice to utilize the waste cold water therefrom for cooling drinking water contained within the cooler.

Another object of the invention is to provide an ice-cooler of elliptical or round in plan to which cover grates are applied for imparting a rectangular or square shape thereto to snugly fit within the particular shape ice compartment, and which grates 20 allow circulation of air within the refrigerator and about said cooler.

A further object is the provision of a water cooler which includes an outer casing, an inner casing contained therein, and a removable cover fitting over said casings and provided with a trough for catching the melted water from the ice adapted to be supported upon said cover, the said trough serving to maintain the side walls of the 30 inner and outer casings in even spaced relation to provide a cold water chamber to receive the water which drips through openings in said trough.

With these and other objects in view, the 35 invention resides in certain novel construction and combination and arrangement of parts, the essential features of which are hereinafter fully described, are particularly pointed out in the appended claims, and are 40 illustrated in the accompanying drawing, in which:—

Figure 1 is a fragmentary vertical sectional view through a refrigerator showing my water cooler in position in the ice compartment thereof.

Figure 2 is a perspective view of the water cooler per se.

Figure 3 is a vertical sectional view on the line 3—3 of Figure 2.

Figure 4 is a detail vertical transverse sectional view on the line 4—4 of Figure 3.

Figure 5 is a detail vertical sectional view through one of the corner gratings.

Figure 6 is a perspective view of one of the corner gratings per se. 55

Referring to the drawing by reference characters, the numeral 10 designates my improved water cooler in its entirety which includes an outer pan like casing 11 which is open at its top and in the present instance is shown as elliptical in plan although the same may be circular or other like configuration. The underside of the casing 11 is provided with feet 12 by which the same may be supported in spaced relation to the bottom of 60 an ice compartment of a refrigerator into which the device is inserted.

Seated within the casing 11 is an inner casing or tray 13 which is of the same configuration as the outer casing but of a smaller size so as to fit within the casing 11 in spaced relation to the walls thereof. The bottom of the tray 13 is provided with feet 14 which rest upon the bottom of the outer casing to maintain the bottom of the inner 70 casing in spaced relation to the bottom of the outer casing in order to provide a water space therebetween.

The free edge of the outer casing terminates in a flange 15 which is disposed on a plane beyond the lower side walls of the same in order to provide a space 16 between the side walls of the two casings for the reception of the trough 17 formed adjacent the outer edges of a cover 18 which fits over the 80 open tops of the casings to close the same. The bottom of the trough is provided with openings 18' through which the water drained from the top passes into the water space provided between the inner and outer 85 casing. The trough 17 serves to maintain the side walls of the two casings in even spaced relation. The cover 18 is provided with filling openings 19 adjacent the front edge thereof while a removable cap 20 normally covers the filling opening to exclude ice water from the interior of the inner casing. The cap 20 is adapted to be removed to facilitate the filling of the inner casing with drinking water or other liquid to be 90 cooled.

Connected to the bottom of the inner casing is an outlet pipe 21 which depends below the bottom of the outer casing and is provided with a valve spout 22 of the usual 105 well-known construction. The valve spout

22 is shown in closed position in full lines in Figure 2 of the drawing and is adapted to be swung to the dotted line position to open the valve and allow the contents of the casing to be dispensed.

5 An overflow pipe 23 is provided in the side wall of the outer casing 11 to limit the high level of the water in the water cooling space between the inner and outer casing.

10 In order to adapt an elliptical or annular shaped casing to a rectangular or square shaped ice compartment, I provide removable corner grates 24 on the side walls of the outer casing and which are attached by inserting pins 25 depending therefrom through openings in lugs 26 extending from the side walls of the outer casing. The inner sides of the grates conform to the curvature of the casing and fit snugly thereagainst while the outer edges of the same are disposed at right angle to each other to provide square corners. The corner grates may be removed if desired, depending upon the size and shape of the ice compartment in which the device is installed.

20 In Figure 1 of the drawing, I have illustrated my invention in position within the ice compartment 27 of a refrigerator 28, there being the lower food compartment 29 directly below the ice compartment and which communicates therewith through an air circulating opening 30 provided in a horizontal partition 31. The device is set in the ice compartment so that the outlet pipe 21 extends through the opening 30 into the lower compartment 29 while the feet 12 support the cooler in spaced relation to the partition 31 to allow the cold air within the refrigerator to freely circulate. The circulation of the air is aided by the open grates 24 which would be prohibited if the cooler were constructed of such size as to entirely close communication between the two compartments 22 and 29. A cake of ice 35 is placed into the filling compartment and is supported by the cover 18 of the cooler and which tends to cool the cover to reduce the temperature of the water contained with the inner casing 13. As the ice melts, the water therefrom drains into the trough 17 and drips into the ice water compartment provided between the two casings. This water of course, remains cool for a considerable length of time and being cooler than the water within the inner casing, the same will aid in cooling the drinking water. Should the entire cake of ice melt, the water therefrom remaining in the water compartment will maintain the refrigerator in a relatively cool condition for a given length of time in order to prevent spoiling of food which may be kept therein. As heretofore explained the spot 22 is turned in order to dispense the contents of the cooler and which is reached when in an installed position

through the door of the lower compartment 29. The overflow pipe 23 may be connected or disposed directly above the drain of the refrigerator so as not to flood the interior of the same.

70 From the foregoing description, it will be seen that I have provided a water cooler for use in lieu of the usual tray provided in the ice compartment of a refrigerator and by which drinking water may always be 75 kept cool for use by utilizing the melted water from the ice. The device when installed will not interfere with the usual air circulation within the refrigerator but instead it will aid in maintaining the refrigerator in a relatively cool condition even after the ice has completely melted.

80 What is claimed as new is:—

1. A water cooler comprising an outer casing, an inner casing supported in spaced 85 relation to the bottom wall of said outer casing, a cover provided with a trough fitting over the tops of said outer and inner casings, the said trough serving to maintain the side walls of the inner casing in spaced relation 90 to the side walls of the outer casing to provide a water compartment between said inner and outer casings, said trough having openings therein for the passage of water 95 from the trough into the water compartment caused by the melting of ice adapted to be supported upon said cover, a filling opening provided in said cover for facilitating the filling of said inner casing with liquid to be cooled, and a dispensing valve for controlling the dispensing of liquid in said inner casing.

100 2. A water cooler comprising an outer casing, an inner casing supported in spaced relation to the bottom wall of said outer casing, a cover provided with a trough fitting over the tops of said outer and inner casings, the said trough serving to maintain the side walls of the inner casing in spaced relation 105 to the side walls of the outer casing to provide a water compartment between said inner and outer casings, said trough having openings therein for the passage of water from the trough into the water compartment caused by the melting of ice adapted to be supported upon said cover, a filling opening provided in said cover for facilitating the filling of said inner casing with liquid to be cooled, and a dispensing valve for controlling the dispensing of liquid in said inner casing, and an overflow outlet in said outer casing for limiting the high level of water 115 in said water compartment.

120 3. In a water cooler for insertion into the ice compartment of a refrigerator, a casing 125 of elliptical configuration in plan for supporting a cake of ice, feet on the bottom of said casing for supporting the bottom in spaced relation to the bottom of the ice compartment in which the device is adapted to 130

be placed, and corner gratings extending from the sides of said casing, flush with the top thereof to square off opposite sides of said casing for snugly fitting into an ice compartment of rectangular shape and to allow air to circulate above and below said casing when in use.

4. In a water cooler for refrigerators, a water casing, and corner gratings removably secured to said casing at opposite sides thereof and extending therefrom flush with the top of said casing.

5. In a water cooler for refrigerators, an outer casing provided with supporting legs, an inner casing fitting within said outer casing and provided with feet for support-

ing the bottom of said inner casing in spaced relation to the bottom wall of said outer casing, a removable cover fitting over said inner and outer casings and provided with a trough adjacent the outer edge thereof, said trough serving to maintain the side walls of said inner and outer casings in spaced relation, the said trough having openings therein for allowing melted water from ice adapted to be supported on said cover to drip into the space between said inner and outer casings to cool a liquid adapted to be contained within said inner casing.

In testimony whereof I have affixed my signature.

MORRIS RAYMOND.
